UNITED STATES PATENT OFFICE.

ISAAC A. BAUM, OF CHICAGO, ILLINOIS.

COMPOSITE DOOR FRAME.

Application filed January 20, 1928. Serial No. 248,156.

My invention relates to buildings and particularly to novel means for framing wall openings therein.

One of the principal objects of my invention is to provide a rigid and unyielding frame particularly for a door opening, together with means readily adapting the frame to receive a wood jamb and molding.

A further particular object is to provide means in connection with such a frame adapting it to be manufactured, handled and shipped in a knocked down condition and to be assembled on the job without the use of special metal working equipment. The desired result is secured by so arranging the parts that the wood blocks carried by the frame and adapted to receive the wood trim serve also as means for receiving nails or screws projected through overlapping metallic portions of the frame. This means together with the interlocking relation of the metallic parts assures a rigid and unyielding frame adapted to support the tile or other wall elements and to receive the wood trim, that is desired in many cases.

The result of such construction is that the wall may be completed with the assurance that there will be no cracks in the plaster at the junction of the frame with the wall, due to shrinkage, warping, or distortion of a wood buck, yet permitting the use of the desired wood trim without special fastening devices therefor.

The invention will be more readily understood by referring to the accompanying drawings, in which—

Fig. 1 is a fragmentary elevation of the end of a door frame constructed in accordance with my invention;

Fig. 2 is an enlarged perspective view of a corner thereof;

Fig. 3 is a perspective view of one of the fastening plates;

Fig. 4 is a plan view of one end of the frame and

Fig. 5 is a sectional view through a completed wall constructed in accordance with my invention.

In the drawings it will be seen that the frame elements indicated generally by the letters A, B, and C are of generally channel shape, the channels comprising a web 10, flanges 11, and margins 12 angularly disposed relative to the flanges and constituting

plaster terminals. The free edge 13 of 55 the margins is rebent to form an undercut portion or plaster key and to serve another purpose later described. One or both sides of the channel members may be constructed as described.

In order to provide simple means of connection between adjacent angularly disposed frame elements, I provide L shaped plates as shown in Fig. 3, the leg 14 of which plates is secured by welding or otherwise to a 60 flange 11 of the channel A, while the leg 15 lies alongside of or immediately adjacent to the corresponding flange 11 of the adjacent channel B. Extending along the inner edge of the leg 15 is a lip 16 bent out from 65 the metal of the leg and adapted to enter and interlock with the space between the undercut portion 13 and the flange of the channel. It will be noted that the angular plates are of considerably greater depth than 70 the depth of the channels and in order to stiffen and unite the plates on opposite sides of the channels and to define the space to be occupied by wall tile, I provide short 75 U shaped members 17, 18. The member 17 is 80 welded, as indicated, to the top channel and to the legs 14 of the plates, while the member 18 is welded at its sides only to the legs 15 of the plates.

The parts as described are constructed in 85 the shop and shipped in knocked down condition. In assembling, the workman merely engages the ends sliding the parts into co-operating and interlocking relation. He will then seat a wood block, such as indicated at 19 in dotted lines in Figs. 1 and 2, and drive nails or screws through the overlapping adjacent portions of the leg 15 of the plates, and the flange of the vertical channel and into the wood block. The block 95 serves as a secure holding means for the nails and assures a permanent uniting of the frame elements without possibility of deterioration. If desired, registering holes 20 may be provided in the shop, the holes being formed slightly smaller than the size of 100 the nails or screws to be used. This is not absolutely essential, however, as due to the relatively thin character of metal employed in the channels, nails may be driven through 105 the two thicknesses without great difficulty.

As shown, the channel members are provided at intervals in their length with

struck out ears 21 which are positioned to hold the wall tile and the frame in rigid relation.

At intervals in the length of the channel frame members I seat wood blocks one of which is indicated at 22 in Fig. 5 which may, if desired, be held in place by nails 23 extending through the flanges of the channel. These spaced blocks serve as means of attachment for a wood jamb 24 and molding 25.

In order to suitably stiffen the channels, I may prefer to provide corrugations 26 at intervals therein as shown in Fig. 1.

While I have shown the interlocking corner clips in a certain relation, it is obvious that changes may be made in this relation and in the general design as to other features without losing many of the advantages of the invention disclosed. Therefore, I do not wish to be limited except as indicated in the appended claims.

I claim:

1. A frame element for wall openings comprising in combination a plurality of metallic channel shaped elements having overlapping portions at their junction angles, said overlapping portions having registering apertures, a wood block within a channel shaped elements and fastening devices extending through the apertures and into the wood block.

2. A frame element for wall openings comprising in combination a plurality of metallic channel shaped elements having overlapping portions at their junction angles, said overlapping portions having registering apertures, a wood block within a channel shaped element, fastening devices extending through the apertures and into the wood block, and trim for the opening secured to said wood block.

3. In means for framing wall openings, the combination of a plurality of metallic channels having overlapping portions at their junction angles, a wood block seated in one of said channels at the point of overlapping of said channels and fastening devices extending through said overlapping portions and into said wood block.

4. In means for framing wall openings, the combination of a plurality of metallic channels associated to form a rectangular frame, one of said channels being provided with an extension overlying and co-operating with an angularly disposed adjacent channel, a wood block in one of said channels, fastening means extending through the overlapping portions and into said wood block, and interlocking means on said extension and adjacent channel for forming a holding connection independent of said fastening means.

5. In a door frame, the combination of metallic channels arranged in rectangular

form, an angular extension from one of said channels adapted to lie alongside the flange of an angularly disposed adjacent channel, said extension and flange being provided with registering apertures, a wood block in the channel and fastening devices extending through said apertures into said block.

6. In a door frame, the combination of a plurality of metallic channels arranged in rectangular form, the flanges of said channels being provided with marginal extensions forming plaster terminals, means projecting from one of said channels alongside the flange of an adjacent channel and interlocking with the marginal extension therefrom, a wood member in the channel and fastening means passing through said extension means and the adjacent channel and into said wood member.

7. In a door frame, the combination of a plurality of metallic channels arranged in rectangular form, the margins of the flanges of said channels being bent to provide plaster terminals, a plate secured to one of said channels and projecting parallel to the flange of an adjacent channel and means on said plate adapted to co-operate and interlock with the plaster terminal of said adjacent channel.

8. In means for framing wall openings the combination of metallic framing members arranged in rectangular form, a metallic element of angle shape rigid with one framing member and adapted for sliding cooperation with another framing member with the cooperating parts in overlapping relation, a wood block held at the junction of said framing member and said angle element, and fastening devices extending through the overlapping metal parts and into said wood block.

9. In means for framing wall openings the combination of metallic framing members arranged in rectangular form, a right angularly disposed extension from one framing member adapted for sliding interlocking cooperation with another framing member, said interlocked parts having registering apertures, a wood block located at the junction of said framing members, and fastening devices extending through said apertures into said wood block.

10. In means for framing wall openings the combination of metallic framing members arranged in rectangular form, a right angularly disposed extension permanently secured to one framing member and adapted for sliding interlocking cooperation with another framing member, said interlocking parts having registering apertures, and fastening devices extending through said apertures.

11. In a door frame, the combination of a plurality of metallic channels arranged in rectangular form, the flanges of said chan-

nels being provided with marginal extensions forming plaster terminals, means projecting from one of said channels alongside the flange of an adjacent channel and interlocking with the marginal extension therefrom, and fastening means passing through said extension means and the adjacent channel.

12. A frame for wall openings comprising in combination, two vertical and one horizontal frame elements, said vertical and

horizontal elements having interlocking and overlapping portions provided with registering apertures when the parts are in final position, wood blocks held at the point of overlap of said portions, and fastening devices extending through the apertures and into the wood blocks. 15

In testimony whereof I have affixed my signature.

ISAAC A. BAUM.
